UNITED STATES PATENT OFFICE.

ARTHUR PATEMAN, OF LEICESTER, ENGLAND, ASSIGNOR TO IMPERIAL TYPEWRITER COMPANY LIMITED, OF LEICESTER, ENGLAND, A BRITISH COMPANY.

RIBBON-REVERSING MECHANISM.

Application filed May 17, 1926, Serial No. 109,800, and in Great Britain June 2, 1925.

This invention relates to the ink-ribbon winding and reversing mechanism of typewriters and has reference to such mechanism of the type corresponding to the following description. In mechanism of the type in question the operation of the reversing means is occasioned by the temporary interengagement, and, it may be, movement in unison, of two normally disengaged members, of which one is a reciprocating member (to be understood as including an oscillating member) operatively connected to the type-keys so as to reciprocate at each depression of the keys. One of these normally disengaged members is maintained by ribbon-controlled means in such a position relatively to the other during the winding and unwinding operations of the winding mechanism that the reciprocating member moves in its path clear of the other member and when the moment arrives for reversing the ribbon-winding mechanism said ribbon-controlled means operates and in consequence the relative positions of the normally disengaged members are altered in such manner that the path of reciprocating movement of the reciprocating member is intercepted by the other member with the result that the temporary interengagement which occasions the actuation of the reversing means is effected.

Hitherto in mechanism of this type the said ribbon-controlled means, which by its operation under the tension of the ribbon occasions the temporary interception of the path of movement of the reciprocating member by the other member, has been so operatively associated with that member of the said two normally disengaged members with which it co-acts that the tension in the ribbon operating through said ribbon-controlled means is caused positively to force the intercepting member into the path of the reciprocating member. This arrangement, however, has proved unsatisfactory in that it tends to fouling of the parts of the mechanism and the present invention has for its principal object to provide an improvement whereby this difficulty is overcome.

For the sake of convenience and brevity the term "catch" will be employed hereinafter in designation of that member of the said two normally disengaged members with which the ribbon-controlled means aforesaid co-acts to bring about the temporary interception of the path of movement of the reciprocating member. Also the position the

catch occupies when the path of movement of the reciprocating member of the two normally disengaged members aforesaid is intercepted by the other member thereof, will be designated the operative position of the catch.

According to the invention, typewriter ink-ribbon winding and automatic reversing mechanism of the type above referred to, is provided whereof the member designated the "catch" is yieldingly operated to its operative position.

Operative connections may be provided between the catch and the ribbon involving a ribbon-controlled detent arranged when operated in one direction to withdraw the catch from its operative position and thereafter to hold the catch against its yielding control out of said operative position and when operated in the reverse direction to release the catch.

Figure 1 is a front elevation of the spool-mechanism at one side of the machine;

Figure 2 is a plan of the mechanism at either side of the machine, with certain parts removed;

Figure 3 is a central vertical section through part of the mechanism; and

Figure 4 represents more or less diagrammatically a horizontal sectional view through the spool along the line 4-4 of Figure 1.

In the various figures like reference characters indicate like parts.

The mechanism comprises as usual two similar units disposed one at either side of the machine and allocated one to the winding-on spool and the other to the winding-off spool. With the parts of the mechanism in the relative positions shown in Figure 2, the unit on the left-hand side of Figure 2 is the one which is allocated to the winding-off spool and the unit at the right-hand side is the one which is allocated to the winding-on spool. It will of course be understood, however, that first the left-hand spool constitutes the winding-off spool and the right-hand spool the winding-on spool and after reverse has been effected the left-hand spool becomes the winding-on spool and the right-hand spool the winding-off spool.

Each unit of the mechanism comprises a central vertical shaft 1 which is stationary and is mounted upon a foundation plate 2 suitably carried by means, not shown, upon the framework 3 of the machine. Mounted upon the shaft 1 so as to be freely revoluble

thereon is a sleeve 4 carrying at the bottom a ratchet-wheel 5. The ratchet-wheel 5 is fixed upon an enlarged portion 6 of the sleeve 4 as shown clearly in Figure 3. The 5 spool 7 is mounted upon the sleeve 4 and rests as shown upon the upper face of the enlargement 6 which constitutes at the top a shoulder to receive the underside of the spool.

10 Between the underside of the spool and the ratchet-wheel 5 there is interposed a disc-shaped plate 8 which will be referred to as the top plate. In Figure 2 this top plate 8 is removed.

15 The spools are each arranged, as usual, to be driven by the depression of any one of the type-keys of the machine and the driving connections between the spool and the type-keys comprise the sleeve 4, the ratchet-wheel 5, a pawl 9 spring-pressed towards the teeth of the ratchet and mounted upon the free end of a lever 10 pivotally carried upon the shaft 1, and other operative connections not forming part of the invention 20 25

30 and shown only in part at 11 in the drawings. The levers 10 on both sides of the machine oscillate in unison once at every depression of any one of the type-keys and with the parts in the relative positions indicated in Figure 2, the pawl 9 of the right-hand unit will engage the ratchet 5 with which it cooperates with the result that the right-hand spool will be driven. Whilst the right-hand spool is being driven in this way

35 the left-hand spool together with the ratchet 5 loosely revolves on the shaft 1, the pawl 9 of the left-hand unit being maintained out of contact with the teeth of the ratchet by means of a projection 12 projecting upwardly from the upper face of a T-shaped lever 13 pivotally mounted to swing in a horizontal plane upon a stud 14 carried upon the bottom plate 2.

40 The T-shaped lever 13 is provided as shown with three limbs, one 15 which carries the projecting pin 12 just referred to, another 16 carrying a second projecting pin 17 and a third 18 which has a short slot 19 at the free end. The pin 17 operates to throw 45 50 55 into and out of engagement with the teeth of the ratchet-wheel 5 a check pawl 20 pivotally mounted upon a stud secured upon the bottom plate 2.

55 Pivotedly mounted upon the shaft 1 and situated just above the lever 10 which may be referred to as the driving lever, is a member 21 formed with several radially projecting arms. This member 21 is provided with a long arm 22 which is operatively connected by a connecting link 23 with the corresponding arm 22 of the right-hand unit so that pivotal movement of the lever 21 of the unit at one side of the machine will occasion corresponding pivotal movement of 60 65 70 75 80 85 90 95 100 105 110 115 120 125 130 the lever 21 at the other side of the machine.

The lever is formed with five arms—the arm 22 just referred to, a pointed arm 24 hereinafter again to be referred to, a somewhat longer arm 25, a fourth arm 26 and a short arm 27. The last-mentioned arm 27 carries a depending pin 28 which is arranged to extend through the slot 19 of the arm 18 of the T-shaped lever 13 and to transmit movement from the lever 21 to the lever 13 when reverse is to be effected.

75 80 85 90 95 100 105 110 115 120 125 130 As stated earlier, the driving-lever 10 oscillates once at every depression of a type-key. When reverse is to be effected a gravity-operated catch 280 is pivotally mounted upon the arm 25 of the lever 21 to swing in a vertical plane, is arranged to drop down into the path of the right-hand arm 29 of the driving lever 10. As will be at once seen, this movement of the catch 280 will result in the lever 21 being moved in unison with the driving lever 10 in the direction of the arrow, at the next depression of a type-key. This movement of the member 21 occasions movement of the lever 13 in a clockwise direction and movement of the two pawls 9 and 20 into operative engagement with the teeth of the ratchet-wheel 5. The immediately preceding operations are those which take place in the unit on the left-hand side of Figure 2. At the same time a reverse set of operations takes place in the right-hand unit of the mechanism. That is to say, the member 21 of the right-hand unit is swung in an anti-clockwise direction, the lever 13 is moved in a clockwise direction and the pawls 9 and 20 are brought out of driving engagement with the teeth of the ratchet. As typing continues it will be readily understood that the drive is transferred by the movements of the parts aforesaid from the right-hand spool to the left-hand spool.

135 The catch 280 is arranged to be normally held up, that is in the position shown in Figure 1, out of engagement with the arm 29 of the driving lever 10 by means of a ribbon-controlled detent 30 pivotally mounted at 31 upon the top plate 8. This detent 30 is provided with two horns 32 and 33 respectively. The horn 33 is arranged to be engaged in a known manner by a projection 34 forming part of a hinged tongue 35 hinged at 36 to the hub of the ribbon-spool, and extending through a slot 37 in the lower flange of the spool so as to engage the edge of the horn 33 of the detent. The other horn 32 is arranged, as shown, to bear upon the front face of the upwardly extending arm 38 of the catch 280 so as to hold the catch in the position shown in Figure 1, when the detent is in the position shown in Figure 2, that is, when the tongue 35 is in the position shown in Figure 4 which is the case in both the winding-on spool and winding-off spool until the tension in the ribbon pulls the tongue 35 of the winding-off spool 140

into the position shown in dotted lines in Figure 4. When this occurs the horn 32 of the detent moves outwardly and allows the catch 280 to drop down to the operative position aforesaid.

If, when the catch drops, the arm 29 of the driving lever 10 be vertically beneath the slot 40 through which the catch 280 drops, the catch will merely ride on top of the arm 29 until the latter moves to the position shown in Figure 2 whereupon the catch will complete its movement.

The detent 30 is arranged to be spring-controlled in a direction to return the catch 280 to the position shown in Figure 1, by means of a tension-spring 41 anchored to a stud 42 secured to the top-plate 8.

The member 21 is arranged to be moved only partially through its operative stroke, 20 by direct thrust from the type-key mechanism. The remainder of its travel is effected in a known manner by means of a spring-controlled lever 43 operating through a roller 44 mounted thereon upon the angled end of 25 the arm 24. The member 21 is moved by positive thrust from the type-key mechanism sufficiently far to carry the point of the arm 24 over the dead-centre of the pin 45 upon which the roller 44 rolls, whereupon 30 the tension in the spring 46 which controls the lever 43 operates to drive home the member 21, whether the movement of said member be clockwise or anti-clockwise.

As will be seen upon reference to the 35 drawings, only the left-hand unit is provided with a spring-controlled lever and roller as set forth in the preceding paragraph. Consequently, the spring-controlled lever 43 provided on the left-hand unit will 40 operate both the left-hand and the right-hand unit, the inter-connecting link 23 transmitting thrust to the right-hand unit.

In order to limit the throw of the lever 10 and thereby ensure that the ratchet-wheel 45 5 shall be advanced one tooth at a time, an adjustable stop 47 is provided on each unit. This stop 47 may conveniently take the form, as shown, of a vertical stud mounted upon the bottom plate 2 so as to be capable 50 of adjustment by rotation thereon and formed with an eccentric at the top. By the partial rotation of the stud the position of the stop relatively to the pawl 9, with the front edge of which the eccentric is arranged to engage, may be adjusted at will.

It is desirable to be able to adjust one unit relatively to the other and for this purpose one of the pins 22^a which connect the link 23 to the arms 22 may have an eccentric portion 23^a engaging, say, the link 23 so that by rotation of the pin the distance 60 between the extremities of the arms 22 may be shortened or lengthened slightly as desired to effect the requisite relative adjustment of the units.

As will be readily appreciated mechanism constructed according to the present invention is not liable to fouling through the unavoidable absence of synchronism of the movements of the two members the temporary interengagement of which occasions the operation of the reversing means.

The particular combination of parts according to the invention is otherwise advantageous as will be appreciated by those acquainted with the art. One advantage of the particular combination of parts according to this invention accruing to the fact that the main operative parts of the mechanism, namely, the levers 10 and 21, are mounted to rotate about a common fulcrum, is that the transmission of motion from the lever 10 to the lever 21 through the catch 280 is rendered easy and direct; there is no sliding friction such as would otherwise occur if the said levers were mounted on separate fulcrums. A further advantage is that it is open to the manufacturer to angularly dispose the various parts of the mechanism as he pleases about the central axis, for example, to clear portions of the mechanism of the machine which would otherwise obstruct the ribbon mechanism.

Instead of the catch taking the form indicated in the drawing it may take any other convenient form and it may be mounted either upon the member which is operatively connected to the reversing means as is the case in the construction described or it may be mounted upon the member which is operatively connected with the type-keys. A further modification might be the provision of a light spring to control the movement of the catch 280. Such modifications are to be understood as embraced within the scope of this invention.

I claim:—

1. Typewriter ink-ribbon winding and automatic reversing mechanism of the class described comprising in combination, ink-ribbon reversing means, two members pivotally mounted to swing about a common axis in proximity to one another, one of said members being operatively connected to the machine type keys so as to oscillate as the latter are depressed, and the other of said members being operatively connected to the ribbon reversing means to operate said means by its swinging movement, a yieldingly controlled member mounted on one of said swinging members to constitute the catch, and capable of movement under its yielding control into the path of the other swinging member to take its operative position in which it locks the two swinging members together whereby in one direction they move in unison, and a ribbon-controlled means for normally holding the catch out of its operative position until reverse is to be effected, and then releasing it.

2. Typewriter ink-ribbon winding and automatic reversing mechanism of the class described comprising in combination, ink ribbon reversing means, two members pivotally mounted to swing about a common axis in proximity to one another, one of said members being operatively connected to the machine type-keys so as to oscillate as the latter are depressed, and the other of said members being operatively connected to the ribbon reversing means to operate said means by its swinging movement, a yieldingly controlled member constituting the catch pivoted to one of said swinging members so as to be capable of swinging under its yielding control into the path of the other swinging member about an axis tangential to the said path to take its operative position in which it locks the two swinging members together whereby in one direction they move in unison, and a ribbon-controlled detent for normally holding the catch out of its operative position until reverse is to be effected, and then releasing it.
3. Typewriter ink-ribbon winding and automatic reversing mechanism of the class described comprising in combination, ink ribbon reversing means, two members pivotally mounted to swing about a common axis in proximity to one another, one of said members being operatively connected to the machine type-keys so as to oscillate as the latter are depressed, and the other of said members being operatively connected to the ribbon reversing means to operate said means by its swinging movement, a gravity operated member constituting the catch pivoted to one of said swinging members so as to be capable of swinging by gravity into the path of the other swinging member about an axis tangential to the said path to take its operative position in which it locks the two swinging members together whereby in one direction they move in unison, and a ribbon-controlled detent for normally holding the catch out of its operative position until reverse is to be effected, and then releasing it.
4. Typewriter ink-ribbon winding and automatic reversing mechanism of the class described comprising in combination, ink ribbon reversing means, two members pivotally mounted to swing about a common axis in proximity to one another, one of said members being operatively connected to the machine type-keys so as to oscillate as the latter are depressed, and the other of said members being operatively connected to the ribbon reversing means to operate said means by its swinging movement, a yieldingly controlled member mounted on one of said swinging members to constitute the catch, and capable of movement under its yielding control into the path of the other swinging member to take its operative position in

which it locks the two swinging members together whereby in one direction they move in unison, and a ribbon-controlled means for normally holding the catch out of its operative position until reverse is to be effected, and then releasing it, said catch member being mounted for sliding engagement with the other swinging member, whereby when the catch is released while said other swinging member is in the path of the catch member, the latter will ride idly upon said swinging member until sufficient relative movement of the parts has taken place to enable the catch to complete its yieldingly controlled movement.

5. In a typewriter provided with two ribbon spools operating alternately as winding-on and paying-off spools, typewriter ink-ribbon winding and automatic reversing mechanism of the class described, including ribbon reversing means, and comprising in combination two members, one for each spool, pivotally mounted to swing about a common axis in proximity to one another, one of said members being operatively connected to the machine type-keys so as to oscillate as the latter are depressed, and the other of said members being operatively connected to the ribbon reversing means to operate said means by its swinging movement, a yieldingly controlled member mounted on one of said swinging members to constitute the catch, and capable of movement under its yielding control into the path of the other swinging member to take its operative position in which it locks the two swinging members together whereby in one direction they move in unison, and a ribbon-controlled means for normally holding the catch out of its operative position until reverse is to be effected, and then releasing it.

6. Typewriter ink ribbon winding and automatic reversing mechanism of the class described comprising in combination, a member pivotally mounted to swing about an axis, and connected to the machine type keys to oscillate as the latter are depressed, a second member pivoted on said axis and connected to the ribbon reversing means, a ribbon spool and a driving ratchet therefor both also mounted on said axis, means for temporarily connecting said two members whereby they oscillate in unison, a driving pawl for said ratchet carried by said first member, a check pawl for said ratchet, and a double bell crank having its central arm pivoted to said second lever, and its two oppositely directed limbs pivoted respectively to said pawls, whereby said pawls are withdrawn from operative engagement with the ratchet.

7. Typewriter ink ribbon winding and automatic reversing mechanism of the class described comprising in combination, a member pivotally mounted to swing about

an axis, and connected to the machine type keys to oscillate as the latter are depressed, a second member pivoted on said axis and connected to the ribbon reversing means, a 5 ribbon spool and a driving ratchet therefor both also mounted on said axis, means for temporarily connecting said two members whereby they oscillate in unison, a driving pawl for said ratchet carried by said first member, a check pawl for said ratchet, and a double bell crank having its central arm pivoted to said second lever, and its two

oppositely directed limbs pivoted respectively to said pawls, whereby said pawls are withdrawn from operative engagement with 15 the ratchet, a second ribbon spool having a similar mechanism as said first spool, and interconnecting means between the two sets of mechanism whereby the reversing means in both sets operate simultaneously, that of 20 one set being driven by the other.

In testimony whereof I affix my signature.

ARTHUR PATEMAN.
